GRINDING MILL

James H. Johns, Los Angeles, Calif.

Application October 23, 1935, Serial No. 46,401

2 Claims. (Cl. 83—45)

This invention relates to improvements in grinding mills.

The principal object of the invention is to produce a device which will grind material and classify it simultaneously, thus eliminating the necessity of separate classifying equipment.

Another object is to separate the fines from the oversize or coarse particles in the material being fed to the grinder.

10 A further object is to provide means for the quick removal of the material as soon as ground to desired fineness, thus reducing overgrinding to a minimum, and producing a product of more nearly uniform size than is now possible in present grinding practice.

A still further object is to produce a device which is of simple construction, one which is economical to manufacture, one which will require a minimum amount of power, and one which will have high efficiency.

20 Other objects and advantages will be apparent during the course of the following description.

In the accompanying drawings forming a part of this specification and in which like numerals are employed to designate like parts throughout 25 the same,

Fig. 1 is a vertical cross section of my device, showing portions thereof in elevation,

Fig. 2 is a fragmentary cross sectional view 30 on the line 2—2 of Fig. 3,

Fig. 3 is a top plan view of the grinder element and a portion of the base thereof.

Fig. 4 is a fragmentary cross sectional view 35 showing the employment of tapered rollers (or rods) as the grinding medium, and

Fig. 5 is a cross sectional view on the line 5—5 of Fig. 3.

40 There are many trades in which it is necessary to grind materials in order to free certain chemicals, minerals, ores, and the like, and it is a grinder for such a purpose that I have devised.

In the accompanying drawings wherein for the purpose of illustration is shown a preferred embodiment of my invention, the numeral 5 designates a base having a plurality of standards 6, which support a bearing 7, directly above a bearing 8, in the base 5. Positioned in these bearings is a hollow shaft 9, to which is secured a casting or shell 11, which has a gear 12, capable 45 of engaging a gear 13, mounted upon a shaft 14. Through this gear arrangement, the casting 11 may be rotated on bearing 32 in the base 5. Secured within the casting are wear plates 16, 33 and 34. Wear plates 16 have a serrated 50 surface, the purpose of which will be later seen.

Connected at the top of shaft 9 is a suitable swivel joint connection 43, for connection to the water feed line for utilizing hollow shaft 9 as a water passage 17, which communicates with a plurality of radial bores 18. Radial bores are connected by a plurality of circular bores 35, and from which bores, vertical bores 19 extend to the surface of the wear plates 16. Suspended above, from bolts 41, which are held by nuts 42 to the standards 6 through the medium of chains 21, 10 is a weighted element 22 also having wear plates 23, 36 and 37 secured thereto. The wear plates 23 are provided with serrated surfaces. Openings 24 extend through the wear plates 23 angularly upward through the weighted element 15. 22. A feed opening 26 extends from the top of the weighted element angularly downward so as to permit material to enter the space between the wear plates 16 and 23. Wear plates 38 are secured to hollow shaft 9.

20 In the form of the device shown in Figs. 1, 2 and 5, I have shown the space between the wear plates occupied by grinding balls of various sizes, which are represented by the circles 27. In the modified form shown in Fig. 4, the grinding action is accomplished by the use of varying sized tapered rollers 28, the other parts remaining the same except that the grinding surfaces of the wear plates under and over the rollers have flat inclined rather than serrated surfaces. Mounted 25 on top of the stationary element are spiral guides 29. A trough (or launder) 31 surrounds the upper edge of the device and is secured by brackets 40 to standards 6 and is adapted to receive and discharge therefrom as will be presently described.

30 Assuming that the parts are arranged as shown in Fig. 1, but with the stationary element raised until clear of the grinding balls, by means of a chain block or other means to release the starting strain and the casting is filled with water and rotated. By this procedure, the power required to start the device is reduced to a minimum. The stationary element 22 is then lowered until its weight rests on the balls. By means of the stationary element, sufficient pressure is applied on 35 the grinding balls to cause them to rotate against the wear plates of the casting 11, of the stationary element 22 and against each other as the casting rotates. Material is dropped on the stationary element so that the same discharges into the opening 26 and passes downwardly into engagement with the grinding balls directly therebelow. Due to the rotation of the casting 11 the balls have a forward movement as they rotate and 40 45 50 55

carry the material with them between the grinding surfaces, becoming thoroughly mixed with it. The rotation and movement of the balls, the weight of the balls themselves, and the pressure 5 of the stationary element on them, cause a very decided grinding and crushing action to take place, which action is sufficient to grind up material fed into the device. Due to the serrated wear plates, greater grinding surface and increased grinding action is obtained. Water is introduced through the bore 17 in. shaft 6 and eventually reaches the bores 19 and is discharged upwardly into the grinding mass. As the material is ground up, the finer particles are carried 10 upwardly by the rising current of water through the openings 24 and the space around the weighted element 22; and due to centrifugal action they are discharged over the lip 39 at top of casting 11 into the trough 31, from which 15 point they are carried to suitable concentrators. Should any of the coarser material not ground sufficiently fine be carried upwardly, it will come to rest upon the top of the weighted element and due to the circular current of water caused by 20 the rotation of casting 11 and shaft 9, it will gradually be carried by the action of the spiral guides back to the opening 26. As the balls become worn and are gradually ground up, additional ones of uniform or varying sizes as the 25 operation designates may be inserted through the opening 26 along with the material being fed. Removal of the balls, replacement and inspection of wear plates etc., may be made through a suitable manhole in the side of the rotor.

30 In the modified form new rollers may be inserted through a suitable manhole in the side of the rotor similar to the one using balls. The worn rollers stay in the device until ground up, thus giving a grinding mass of varying sized 35 rollers, the same as the balls. It will thus be apparent that with my device a very decided grinding and classifying process takes place, the material staying in the device until it has been 40

ground to the fineness desired, this being accomplished and governed by the amount of water introduced into the device.

It is to be understood that the form of my invention herewith shown and described is to be 5 taken as a preferred example of the same and that various changes relative to the material, size, shape and arrangement of parts may be resorted to without departing from the spirit of the invention or the scope of the subjoined claims. 10

Having thus described my invention, I claim:—

1. In a device of the character described, a base, a rotary element mounted on said base, a stationary element loosely suspended in said rotating element, serrated wear plates carried by each 15 of said elements, grinding means interposed between said wear plates, an inclined feed passage extending through said stationary element and inclined downwardly in the direction of rotation of said rotating element, discharge means extending upwardly through said stationary element, spiral guides positioned on said stationary element, said guides being capable of conducting coarse material to said downwardly inclined feed passage. 20

2. In a device of the character described, a base, a rotary element mounted on said base, a stationary element loosely suspended in said rotating element, serrated wear plates carried by each of said elements, grinding means interposed 30 between said wear plates, an inclined feed passage extending through said stationary element and inclined downwardly in the direction of rotation of said rotating element, discharge means extending upwardly through said stationary element, spiral guides positioned on said stationary element, said guides being capable of conducting coarse material to said downwardly inclined feed passage, and means for elevating said stationary member, said flexible suspending means also 35 permitting a partial rotation of said stationary element. 40

JAMES H. JOHNS.
